CLAIM

The ornamental design for a beverage container, or similar article, as shown and described.

DESCRIPTION

FIG. 1 is a top plan view of a beverage container showing my new design;

FIG. 2 is a front elevational view thereof;

FIG. 3 is a right side elevational view thereof;

FIG. 4 is a rear elevational view thereof;

FIG. 5 is a left side elevational view thereof; and,

FIG. 6 is a bottom plan view therefor.

The broken line showing the ground and grass in FIGS. 2-5 is for illustrative purposes only and forms no part of the claimed design.

FIG. 1

FIG. 2

FIG. 3

FIG. 4

FIG. 5

FIG. 6
